UNITED STATES PATENT OFFICE.

DANIEL CARTER, OF TORONTO, ONTARIO, CANADA, ASSIGNOR OF ONE-HALF TO JAMES D. B. McNEICE AND ALBERT JAMES MERRIFIELD, BOTH OF TORONTO, ONTARIO, CANADA.

GAS LIGHTING AND EXTINGUISHING APPARATUS.

1,269,049.

Specification of Letters Patent. Patented June 11, 1918.

Application filed March 31, 1917. Serial No. 159,003.

To all whom it may concern:

Be it known that I, DANIEL CARTER, a subject of the King of Great Britain, residing at the city of Toronto, in the county of York 5 and Province of Ontario, Dominion of Canada, have invented certain new and useful Improvements in Gas Lighting and Extinguishing Apparatus; and I hereby declare that the following is a full, clear, and exact 10 description of the same.

This invention relates to certain new and useful improvements in gas lighting and extinguishing apparatus comprising a main gas burner, a gas-pipe leading thereto, and 15 a spring-closed stop cock controlling the flow of gas through the gas-pipe to the burner, and it relates more particularly to a thermostatically-actuated detent, which immediately becomes operative, and remains 20 so, when the gas at the burner is ignited, to hold the stop cock in open position, which remains inoperative when the gas fails to ignite, and which automatically becomes inoperative and releases the stop cock when the 25 gas is intentionally or inadvertently extinguished, so that the stop cock may automatically turn to closed position under the influence of the closing spring; the object of the invention being to at least minimize, 30 if not entirely eliminate, the risk of accident resulting from a discharge into the atmosphere of unburned hydrocarbon gas, should it fail to ignite, or become extinguished, with the stop cock open.

35 In the drawings:

Figure 1, is a fragmentary elevation of the gas lighting and extinguishing apparatus;

Fig. 2, is a similar view, looking at the parts from the opposite side to that shown 40 in Fig. 1;

Fig. 3, is a detail view of the stop cock and detent plate;

Fig. 4, is a detail view of the actuating lever, by which the stop cock is turned to 45 open position, and the detent is released for the return of the stop cock to closed position;

Fig. 5, is an elevation of the stop cock and actuating lever;

50 Fig. 6, is a side elevation of the thermostatic detent;

Fig. 7, is a front elevation of the same;

Fig. 8, is a plan view of the bracket shown in Figs. 6 and 7;

Fig. 9, is a detail view of the thermostatic 55 spring, on a larger scale than the preceding views, showing the contraction of the spring, when cold, to exert a pressure upon the detent lever and hold the detent dog out of operative relation with the stop cock detent; and 60 showing, in dotted lines, its expansion, when heated, to relieve the lever of such pressure and permit of the movement of the detent dog into operative relation with the stop cock detent, and Fig. 10, is a detail view of 65 the adjustable bracket for the detent lever.

Like characters of reference refer to like parts throughout the specification and drawings.

*a*⁴ represents the main gas burner, *b*⁴ the gas-pipe leading thereto, *c*⁴ the stop cock controlling the flow of gas through the gas-pipe, *f*⁴ the stop cock casing, *d*⁴ the pilot pipe, and *e*⁴ the pilot burner for igniting the 70 gas at the main burner.

As shown in Figs. 1 and 2, the stop cock is extended beyond both sides of the casing *f*⁴, and is provided on one side of the casing with an arm *g* and on the other side of the casing with a detent plate *y* having a detent tooth *y'*, the arm *g* and detent plate *y* being 75 movable with the stop cock.

In juxtaposition to the detent plate *y*, is a detent dog *y'*, forming part of a detent lever *a''* fulcrumed to some appropriate 80 part of the gas fixture, and extending to the vicinity of the burner *a*⁴.

As shown in Fig. 1, the lever *a''* is fulcrumed to a stud *b* projecting from a bracket *c* adjustable on the pilot pipe *d*⁴, whereby 85 the detent dog *y'* can be accurately positioned with regard to the detent tooth *y'*, and respectively moved, out of its path by the contraction and into its path during the expansion, of the thermostatic spring *j*⁴, 95 hereinafter described.

The lever *a''* is provided with an arm *b''*, between the fulcrum *b* and the detent dog *y'*, and connected to the arm *b''* and to a stud *c''*, adjustable on the pilot pipe, is a 100 tension spring *d''* to move the detent dog into the path of the detent tooth when the

thermostatic spring j'' is expanded, so that when the stop cock is turned to open position, the detent dog y' will engage the detent tooth y'' and hold the stop cock against 5 closing movement while the gas is ignited.

Slidable on the lower end of the pilot pipe, is a collar f'' , to which is attached a bracket g'' slotted at h'' for the lever a'' passing through it, the dimensions of the slot h'' being sufficient to permit of the rocking movement of the lever as it turns on its fulcrum.

The lower end i'' of the lever a'' is tapered, and is engaged by the thermostatic spring j'' riveted to the bracket g'' in the 15 vicinity of the burner a^4 .

As shown in full lines in Fig. 9, the thermostatic spring j'' is of a curved shape, with the free end of the arc engaging the tapered end of the lever, and, when cold, exerting a 20 pressure upon the lever b'' sufficient to throw the detent dog y' out of the path of the detent tooth y'' , so that the stop cock will be free to close.

When the gas is ignited, either at the pilot 25 or main burner, the heat therefrom will expand the thermostatic spring j'' , as shown in dotted lines in Fig. 9, which, as a result of such expansion, relieves the tapered end of the lever a'' of its pressure, and enables 30 the tension spring d'' to throw the detent dog y' into the path of the detent tooth y'' , so that if the stop cock is open, the detent tooth y'' will remain engaged with it, or if the stop cock is closed, it will be positioned 35 to engage with the detent tooth y'' when the stop cock is manually opened.

Loosely mounted on, and rotatable independently of, the stop cock c^4 , is a hub z , movable laterally toward and away from 40 the detent plate y , the hub z having a lever arm z' , to which is attached a pull chain or cord z^4 , by which the stop cock may be manually actuated.

Forming part of the hub z , is an offset z'' 45 normally engaging the detent dog y' , and maintained in contact therewith by a tension spring a' which presses the hub z into contact with the detent plate y for that purpose, and returns the hub and arm to their 50 initial position when the strain on the pull chain or cord is released.

When the pull chain or cord is strained, the arm z' and hub z are turned from the position shown in full lines in Fig. 1, to the 55 position shown in dotted lines in the same figure. This turning movement of the arm brings an offset e' on the hub z into engagement with a pin e'' on the detent plate y and turns the detent plate and stop cock in 60 unison with the hub z until the stop cock is fully opened and the detent tooth y'' positioned to be engaged by the detent dog y' .

If the pilot light and burner flame, or either of them, is ignited, the heat therefrom

will expand the thermostatic spring j'' and 65 permit of the tension spring d'' moving the detent dog y' into position to engage the detent tooth y'' , and remain engaged therewith while the gas at the burner or pilot remains ignited.

When the strain on the pull chain is released, the arm z' and hub z return to their normal position under the influence of the tension spring a' , the offset z'' , during such return, clearing the detent dog y' which, 70 as shown in Fig. 7, has an inclined side y^3 in the path of the offset, so that when the lever and hub reverse their movement under the influence of the tension spring a' , the engagement of this offset z'' with the inclined side y^3 of the detent dog will press the hub laterally from the detent plate and enable the offset z'' to clear the detent dog for the completion of its return movement.

When the arm z' and hub z have returned 85 to their initial position and the offset is clear of the detent dog, the tension spring a' will press the hub z again into contact with the detent plate, which brings the offset z'' again into operative relation with the de- 90 tent dog.

When it is desired to close the stop cock, the pull chain is strained until the arm z' and hub z are turned from the position shown in full lines partly to the position 95 shown in dotted lines, in Fig. 1.

During this movement, the offset z'' engages the detent dog y' and presses it away from the detent tooth y'' , allowing the stop cock to start its closing movement under the 100 influence of the tension spring g' , which is connected to an arm g^5 projecting from the arm g and to the casing f^4 , there being sufficient lost motion between the pin e'' and offset e' to permit of the detent tooth y'' passing 105 clear of the detent dog y' while the detent dog is pressed out of its operative position by the offset z'' .

When the strain on the pull chain is released, the tension spring a' restores the 110 hub z and arm z' to their initial position, and the detent dog y' and detent lever a'' are restored to operative relation with the detent tooth y'' , should the thermostatic spring j'' be heated, but, if the thermostatic 115 spring is cold, it will engage the tapered end of the lever a'' and hold the detent dog out of operative relation with the detent tooth.

From the foregoing description, it will be ascertained that when the thermostatic 120 spring j'' is heated, it will expand sufficiently to permit of the free action of the corresponding end of the detent lever a'' , to allow of the tension spring d'' throwing the detent dog into the path of the detent tooth y' , and maintaining it there while the thermostatic spring remains expanded, such 125 expansion existing while the gas at the

burner or pilot remains ignited, and that when the thermostatic spring is contracted, it will exert a pressure on the corresponding end of the lever *a'* to force the detent dog 5 out of the path of the detent tooth, so that the stop cock will be free to move to closed position, this movement, being automatically and instantaneously effected by the spring *g'*.

10 It will also be ascertained that by means of a construction similar to that previously described, it is possible to minimize, if not entirely eliminate, the danger resulting from a failure to ignite the gas when the 15 stop cock is opened, and the danger resulting from the intentional or inadvertent extinguishing of the flame with the stop cock open, and it will be understood that various alterations may be made in the structural 20 details above described, without departing from the principle of the invention.

Having thus fully described the nature of my invention, what I claim as new and desire to secure by Letters Patent, is:—

25 1. In a gas lighting and extinguishing apparatus, the combination of a gas burner, a spring-closed stop cock therefor, a lever to effect the opening movement of the stop cock and having a return movement independently thereof, detent means holding the 30 stop cock in open position when the gas is ignited, and thermostatic means rendering the detent means inoperative when the gas fails to ignite and when the flame has been 35 extinguished, the detent means causing a lateral movement of the lever when turned to fully open the valve to enable the lever to return to its normal position independently of the stop cock, and being rendered 40 inoperative by a partial movement of the lever.

2. In a gas lighting and extinguishing apparatus, the combination of a gas burner, a spring-closed stop cock therefor, a thermostatically-actuated detent, holding the stop 45 cock in open position when the gas is ignited, and inoperative when the gas fails to ignite and when the gas is intentionally or inadvertently extinguished, and a lever to 50 open the stop cock when turned in the opening direction, said lever being returnable to a normal position independently of the stop cock.

3. In a gas lighting and extinguishing apparatus, the combination of a gas burner, a 55 spring-closed stop cock therefor, a thermostatically-actuated detent, holding the stop cock in open position when the gas is ignited, inoperative when the gas fails to ignite and when the gas is intentionally or inadvertently extinguished, and a lever to 60 open the stop cock when turned in the opening direction, a partial movement of the lever rendering the detent inoperative, and

the detent on a complete operation of the 65 lever causing the lateral movement of the lever for its return to a normal position independently of the stop cock.

4. In a gas lighting and extinguishing apparatus, the combination of a gas burner, a 70 spring-closed stop cock therefor, a thermostatic detent holding the stop cock in open position, a laterally-movable rotatable lever for turning the stop cock to open position, returnable to a normal position independently of the stop cock, and means to cause the lateral movement of the lever to clear the thermostatic detent. 75

5. In a gas lighting and extinguishing apparatus, the combination of a gas burner, a 80 stop cock therefor, a lever, a clutch to cause the united movement of the stop cock and the lever when operated to turn the stop cock to open position, said lever having a limited lateral movement, a thermostatic 85 detent holding the stop cock in open position when the gas is ignited and being inoperative when the gas fails to ignite and when the gas has been extinguished, the thermostatic detent having an inclined side 90 to engage with, and cause the lateral movement of, the lever when turned to fully open the stop cock for its return to normal position. 95

6. In a gas lighting and extinguishing apparatus, the combination of a gas burner, a stop cock therefor, a lever, a clutch to cause the united movement of the stop cock and the lever when operated to turn the stop cock to open position, said lever having a limited lateral movement, a thermostatic detent holding the stop cock in open position when the gas is ignited and being inoperative when the gas fails to ignite and when the gas has been extinguished, the 100 thermostatic detent having an inclined side to engage with, and cause the lateral movement of, the lever when turned to fully open the stop cock for its return to normal position, a partial movement of the lever rendering the thermostatic detent inoperative. 105 110

7. In a gas lighting and extinguishing apparatus, the combination of a gas burner, a spring-closed stop cock therefor, a thermostatic detent to hold the stop cock in its 115 open position when the gas is ignited, being inoperative when the gas fails to ignite and when the flame has been extinguished, an oscillating lever having a clutch to turn the stop cock to open position, said lever returning to a starting position independently of the stop cock, said lever having a limited lateral movement, and means to cause the lateral movement of the lever to clear the detent as it returns to a starting position. 120 125

8. In a gas lighting and extinguishing apparatus, the combination of a gas burner, a spring-closed stop cock therefor, a detent

plate mounted to turn with the stop cock, a lever loosely mounted on the stop cock having limited lateral movement, a thermostatic detent to hold the stop cock in open position when the gas is ignited, being inoperative when the gas fails to ignite and when the flame has been extinguished, said thermostatic detent having an inclined side

to cause the lateral movement of the lever for its return to normal position.

Toronto, March 3rd, 1917.

DANIEL CARTER.
